UNITED STATES PATENT OFFICE.

JAMES C. HYDE, OF WEST HAVEN, CONNECTICUT, ASSIGNOR TO THE WEST HAVEN BUCKLE COMPANY, OF SAME PLACE.

GARMENT-CLASP.

SPECIFICATION forming part of Letters Patent No. 297,803, dated April 29, 1884.

Application filed March 17, 1884. (No model.)

To all whom it may concern:

Be it known that I, JAMES C. HYDE, of West Haven, in the county of New Haven and State of Connecticut, have invented a new Improvement in Garment-Clasps; and I do hereby declare the following, when taken in connection with accompanying drawings and the letters of reference marked thereon, to be a full, clear, and exact description of the same, and which said drawings constitute part of this specification, and represent, in—

Figure 1, a front view; Fig. 2, a sectional side view; Fig. 3, one of the jaws, showing the wire loop attached and extended to form the closing-springs; Fig. 4, a perspective view of the wire loop detached.

This invention relates to an improvement in garment-clasps such as used for stocking-supporters and like purposes, and particularly to that class which consists of a pair of jaws hinged together midway of their length, with a spring between forcing the two ends together to clasp the garment, the end of one attached to the strap, the other free, the two ends serving as handles, by which the jaws may be bent against the pressure of the spring, the object of the invention being principally to provide the upper or tail end of the jaws with a guard to prevent interference with the garments, and make the tail portion principally of wire; and the invention consists in the construction as hereinafter described, and more particularly recited in the claims.

A represents one jaw, and B the other, the two hinged together by a pintle, a, the two jaws extending above the pintle in the usual manner, and so that the action of the spring may be applied above the pintle, tending to force the meeting or lower ends of the jaws together.

As usually constructed, the spring has been a helical spring arranged around the pintle, one leg extending to bear upon one jaw, and the other upon the opposite jaw.

The loop C, by which the clasp is attached to the strap, is made from wire, bent midway of its length to form the loop C; its two legs b c, extending downward, are each coiled to

form helical springs d e, the extreme ends f f turned up toward the loop, as seen in Fig. 4. 50

The part B of the clasp is constructed with a pair of ears, h h. The two legs b c of the loop part are placed upon the part B to bring the springs d e in line with the pintle a; then, the two parts set together, the pintle is introduced, passing through the springs, as seen in Figs. 2 and 3. The ears h h are closed down upon the legs, so as to firmly unite the jaw B to the legs of the loop C. The legs f f of the spring bear against the opposite jaw, A, as 60 seen in Fig. 2, and so that by bringing the two upper ends of the jaw toward each other, the lower or meeting ends will open to grasp the garment, and, left free, the spring will forcibly close the parts. 65

The guard consists of a piece of wire bent into U shape, the bend i of the U inclosed by the upper end of the jaw A turned over it, as at l, Fig. 2. The two legs m extend up and are hooked upon the loop, as seen in Figs. 1 70 and 2. This connection forms a hinge between the guard and the jaw, as also between the loop and the guard, and so as to permit the jaws to be opened, as seen in broken lines, Fig. 2, the joint between the legs m m and the 75 loop yielding for this purpose.

The legs m m form a guard and prevent the tail end of the jaw A from catching upon the garments.

The loop and springs may be formed and applied as shown without necessarily employing the guard m m; or some other guard may be employed instead of the wire guard m m. I therefore do not wish to be understood as limiting my invention to the necessary combination of the guard with such a loop and spring. 85

Instead of extending both legs of the loop to form two separate springs d e, a single spring may be sufficient—that is, one leg only 90 may be extended to form such spring.

I claim—

1. The combination of the two hinged jaws A B, the wire loop C having its two legs fixed to the tail of one of the jaws and extended to form a helical spring between the 95

two jaws, the end of the spring arranged to bear upon the opposite jaw, substantially as described.

2. The combination of the two hinged jaws 5 A, B, the wire loop C attached to the tail of one of the jaws, the said loop extended to form a helical spring between the two jaws, and

so as to bear upon the opposite jaw, with the wire guard m m hinged to the said other jaw and to the loop, substantially as described.

JAMES C. HYDE.
